Inventor:

UNITED STATES PATENT OFFICE.

WILLIAM A. DUTTON, OF CLEVELAND, OHIO.

CAR-TRUCK.

SPECIFICATION forming part of Letters Patent No. 469,011, dated February 16, 1892.

Application filed October 26, 1891. Serial No. 409,840. (No model.)

To all whom it may concern:

Be it known that I, WILLIAM A. DUTTON, a citizen of the United States, and a resident of Cleveland, county of Cuyahoga, and State of Ohio, have invented certain new and useful Improvements in Car-Trucks, of which the following is a specification.

This invention relates to trucks for street-cars; and it consists in the peculiar construction and adaptation of the car journal-boxes with the side bars, substantially as hereininafter described, and pointed out in the claims.

In the accompanying drawings, Figure 1 is a side elevation of one end of a side bar and a journal-box combined. Fig. 2 is a top or plan view of the same. Fig. 3 is a vertical section through the journal-box on line 3 3 of Fig. 1. Fig. 4 is a detached view of the lower part of journal-box.

20 A, from point *a* to *a* on Figs. 1 and 2, is a malleable-iron casting containing the upper part of the journal-box *b* and also having seats *c* *c* for the springs *CC* and holes for the spring-bolts *c*² *c*². In each end of the said casting are provided side recesses, into which bars *D* *D'* are securely fastened by rivets *d* *d*. The bars *D* are those which connect two of the castings *A*, comprising the two side journal-bearings for a car-truck. The bars *D'* are for supporting an outer spring-seat *c*³, in which a third spring *C*² is provided. The lower part of the journal-box *E* (seen detached in Fig. 4) is firmly bolted to the said casting *A* by bolts *e* *e*, and it is also provided with a depending flange having a diagonally-recessed portion *e*². *F* *F* are brace-bars, the lower ends of which are firmly bolted in the said recesses *e*², and their upper ends are firmly bolted to the side bars *D'*, thus forming an extra support for the outer springs.

25 *G* represents a part of a cross-beam for joining two side bars of a truck and from which the brake-beams may be suspended.

To the inner ends of the journal-boxes are 40 provided dust-guards consisting of a chamber

H, formed partly on the upper portion of the journal-boxes and partly on the lower portion. On the axles are provided collars *h*, which rotate in the said chambers, on each side of which are placed leather or other suitable flexible disks *h*², bearing against the sides of the chamber and the sides of the collar for closing the space and preventing the ingress of dirt.

In the lower portions of the journal-boxes 55 may be provided a lubricant and suitable means for conveying the lubricant to the journal.

50 *I* is a corner cap-piece removably attached by bolts in the ears provided for the purpose for the convenience of ingress to the boxes and for putting in the lubricant.

Having described my invention, I claim—

1. In car-trucks, a yoke and part of journal-box and having seats for springs cast in one 65 piece, in combination with lower portion of journal-box *E*, adapted to hold a lubricant, substantially as described.

2. In car-trucks, a yoke and upper part of journal-box having seats for springs cast in one 70 piece and an extension spring-seat *c*³, in combination with lower portion of journal-box *E*, substantially as described.

3. In car-trucks, a yoke and upper part of journal-box having dust-guard chamber, the 75 lower part of journal-box also having portion of dust-guard chamber, in combination with axle having collar *h* and flexible disks *h*², adapted to operate substantially as and for the purpose specified.

4. In car-trucks, a yoke having part of journal-box and seats for springs cast in one piece, a lower portion of journal-box *E*, bolted to said upper part, and the brace-bars *F* *F*, in combination, substantially as and for the purpose set forth. 85

WM. A. DUTTON.
